(Model.)

J. KANE.

AUTOMATIC FIRE EXTINGUISHER.

No. 245,383.

Patented Aug. 9, 1881.

UNITED STATES PATENT OFFICE.

JOHN KANE, OF PHILADELPHIA, PENNSYLVANIA.

AUTOMATIC FIRE-EXTINGUISHER.

SPECIFICATION forming part of Letters Patent No. 245,383, dated August 9, 1881.

Application filed June 6, 1881. (Model.)

To all whom it may concern:

Be it known that I, JOHN KANE, a citizen of the United States, residing at Philadelphia, in the county of Philadelphia and State of 5 Pennsylvania, have invented a new and useful Automatic Fire-Extinguisher, of which the following is a specification.

My invention relates to improvements in automatic fire-extinguishers, in which the heat of 10 a burning building acts upon a combustible or explosive cartridge and opens a water-cock to irrigate the interior of the building. I attain this object by a mechanism illustrated in the accompanying drawings, in which—

15 Figure 1 is an elevation of the entire machine. Fig. 2 is a vertical section of the complete extinguisher; and Fig. 3 is a top view of the collar, showing the arms *in situ*, two of which are in section.

20 Similar letters refer to similar parts throughout the several views.

The thread *e* on the cap *A* secures the machine to a water pipe or main. This cap *A* is secured to a second perforated cap, *B*, by a 25 thread. The cap *A* has a socket, *h*, which receives the head of the valve *C*. The cap *B* has a milled rim, *l*, by which it is adjusted to regulate the valve *C*. This cap *B* is perforated by a hole, *L*, through which passes the valve-rod *D*, and it admits of a column of water in 30 addition. The portion or cap *B* extends through the collar *E* and rests on the base of the arm *G*, into which it is screwed. The collar *E* swings freely about the elongated portion of the cap 35 *B*, resting upon the base of the arm *G*. The portion *B* is perforated by an opening, *L*, running longitudinally through it, and opening by the holes *b* into the space *M*.

The collar *E* has a hollow center or space, 40 *M*, and is provided with radiating arms *F* and *F'*, four in number, which are perforated along their entire length. The extreme tip is closed by a plug, and a slot, *d*, is cut horizontally in the side of each arm its entire length, for the 45 egress of water. These arms are set so that two of them will have the slot on the outer curve of the arm and the other two will have the slot on the inner curve of the arm, the object of which arrangement is to spread the 50 water more uniformly over any given surface,

the arm having the slot on the greater curve throwing the water to a greater distance, while the arms with the slot on the lesser curve throw the water to a less distance, or near the center of the circle of irrigation.

55

The arm *G* has a forked projection, *z*, into which is secured the cap end of a metallic cartridge, *H*. The ball of this cartridge *H* is perforated with a hole, and is slipped onto the rod *I*. This rod *I* is secured to the valve-rod 60 *D* by a collar, *J*, and set-screw *c*.

The mechanism operates as follows: The cap *A* is screwed into a water-main, which makes a connection between *K* and the column of water in the main. The metallic cartridge *H* 65 is then adjusted to the arm *G* and fitted to the pin *I*. The head of the valve *i* is brought up against the valve-seat *h*, and the collar *J* clamped by the set-screw *c*, which holds the valve *i* in contact with the seat *h* and prevents the flow of water. When a fire occurs 70 the cartridge *H*, which is filled with material which is easily explosive, explodes, which drives the valve-rod *D* and valve *i* down and opens the water-main *K*. The water then fills the 75 chamber *C*, rushes through *L*, and emerges through the openings *b* into the space *M*; thence it rushes through *a* into the hollow arms *F* and *F'*, and by a reverse pressure sets them rotating, which spreads a spray of water in all directions, irrigating the space beneath it for 80 many feet.

I do not claim the broad principle of a rotary automatic fire-extinguisher; but

What I do claim, and desire to secure by 85 Letters Patent, is—

1. The combination of a cap, *A*, with a cap or plug, *B*, having a collar, *E*, provided with hollow arms *F* and *F'*, an arm, *G*, carrying a cartridge, *H*, with a pin, *I*, and collar *J* attached to the valve-rod *D*, all substantially for the purpose and as described.

2. The metallic cartridge *H*, combined with the arm *G*, and pin *I*, and collar *J*, all for the purpose and as described.

JOHN KANE.

In presence of—

FREDK. A. SOBERNHEIMER,
JOHN MCKEE.
